UNITED STATES PATENT OFFICE.

PAUL M. HOTCHKIN, OF CHICAGO, ILLINOIS.

ELECTRIC-LIGHT SOCKET.

1,173,803.

Specification of Letters Patent. Patented Feb. 29, 1916.

Application filed May 22, 1912. Serial No. 698,963.

To all whom it may concern:

Be it known that I, PAUL M. HOTCHKIN, citizen of the United States, residing at Chicago, in the county of Cook and State 5 of Illinois, have invented certain new and useful Improvements in Electric-Light Sockets, of which the following is a specification.

My present invention has relation to a terminal fitting for installing electric lights 10 in fixtures, and the object of my invention is the provision of a fitting which may be employed in conjunction with a large variety 15 of fixtures.

I attain the object by the structure illustrated in the accompanying drawings, in 15 which:—

Figure 1 is an elevation of my invention having a lamp socket installed therein and carrying a reflector bracket for holding the 20 reflector in proper relation to said lamp; Fig. 2 is a fragmental partially sectional view centrally of a terminal fitting having a conduit receiving opening in its bottom wall; Fig. 3 is a plan of the open end or top 25 of the terminal fitting shown in Fig. 1, and Fig. 4 is a plan of the closed end or bottom of the fitting shown in Fig. 1.

The terminal fitting comprises a metallic casing 5, substantially cylindrical in form, 30 one end of which is turned outward and provided with extending ears 5^a, which are provided in turn with the interiorly threaded screw holes 5^t. Into the cylindrical casing 5, is inserted a procelain or other insulating 35 socket 6, which has an enlarged top portion provided with ears or lugs 6^a coinciding with the ears 5^a of the casing and bored to register with the screw holes 5^t thereof.

In the sides and bottom of the casing, are 40 openings 10 having integral extension collars 5^b around the peripheries thereof. The collars 5^b are interiorly threaded as at 5^d to receive the threaded ends (not shown) of any conduit pipes which it is desired to 45 connect therewith and for which they provide secure attaching means.

To the face of the insulating socket 6, is 50 removably attached a metallic cover 7, having laterally extending flanges 7^a, which are similar to and register with the flanges 5^a upon the casing 5. A bolt, 7^b, passes through the registering holes in the respective flanges 5^a, 6^a, and 7^a, securing the entire structure firmly together. The cover 7, has a central

opening about which there is a laterally extending annular rim and to this rim, by means of the screws 8^a or any other suitable means, is secured a reflector supporting frame 8, which at proper points, usually three being enough, are secured by rivets or 55 screws 8^c or otherwise, laterally extending spring arms 8^b for engaging and holding the reflector, not shown. The flanges 7^a of the cover 7, instead of being bored to receive the screw 7^b, are provided with open 60 slots as clearly shown in Fig. 3, so that the cover may be placed in assembly with the screws 7^b after they have been inserted in the socket 6, and screwed into the holes 5^t. At one point adjacent the slots the flanges 70 are turned up to form lugs 7^d which are adapted to engage the head of the screw and hold the cover against accidental displacement until the screw has been loosened so as to avoid said lugs. A cutaway portion 75 7^e is also provided adjacent each slot so that after the screw has been loosened somewhat and the cover revolved slightly, it may be readily removed by exerting a little force on the cover. This terminal fitting has provided in the bottom thereof an insulating 80 pad 10^a, and in the collars 5^b are set screws 5^e to secure them to the tubular conduits commonly employed in connection with such work. Formed in the way described, 85 this terminal socket can be used in connection with any form of installation which at present has been brought to my attention and with vertical or horizontal conduits. If only one of the connections 5^b is needed, the 90 others may be closed by suitable plugs.

Having thus described my invention, what I claim as new and desire to secure by Letters Patent, is:—

In a combination with an outlet box comprising a casing having laterally extending flanges, an insulating socket arranged in said casing, flanges integral with said socket alining with the flanges of said casing, a cover for the insulating socket conforming 95 to the shape thereof, and means for clamping the cover and socket to the box.

In testimony whereof I affix my signature in the presence of two witnesses.

PAUL M. HOTCHKIN. 105
